UNITED STATES PATENT OFFICE

NATHANIEL C. MARMON, OF CALDWELL, IDAHO

DESIGN FOR A SUPPORTING DEVICE FOR BROOMS OR SIMILAR ARTICLES

Application filed August 4, 1931. Serial No. 40,779. Term of patent 7 years.

To all whom it may concern:

Be it known that I, NATHANIEL C. MARMON, a citizen of the United States, residing at Caldwell, in the County of Canyon and State of Idaho, have invented a new, original, and ornamental Design for a Supporting Device for Brooms or Similar Articles, of which the following is a specification, reference being had to the accompanying drawings forming part thereof.

In the drawings:—

Figure 1 is a perspective view of the supporting device for brooms or similar articles showing my new design.

Figure 2 is a view in side elevation of the supporting device.

I claim:—

The ornamental design for a supporting device for brooms or similar articles, as shown.

NATHANIEL C. MARMON.
